TANNING APPARATUS

Charles Kannel, Cleveland, Ohio

Application October 22, 1936, Serial No. 107,079

14 Claims.

(Cl. 149—21)

The present invention relates to improvements in hide tanning apparatus, and has as its primary object to facilitate the process of tanning so as to materially reduce the time required for effecting thorough penetration or "striking" of the tanning liquor into the hide.

It has heretofore been proposed in the generally approved method of tanning hides to hang the hides on or over supporting sticks, and to slowly reciprocate the hides so disposed up and down in a vat of liquor, but such operation usually takes from two to three months to produce proper tanning results, primarily due to the position and movement of the hides, which is such that the liquor cannot effectively attack or strike through the hides, particularly the thicker portion at the center line of the hides.

In carrying out my method, however, I employ a novel arrangement of frames upon which the hides are so fastened that in the reciprocation and oscillation of said frames the liquor in which they are immersed is pocketed by the hides with such force or pressure as to cause it to penetrate even into the thickest portion of the hide in a very short period of time compared with that of the former "rocking" processes.

More specifically, my invention comprises a series of open hide-supporting frames arranged in V-formation, or a series of such formations, zigzagging back and forth in a rack from one end to the other, said frames allowing the hides to be attached thereto with the center line of each hide at the apex of the V. Thus, the hides alternate in the direction of facing and receive the full force of pressure of the liquor at each reciprocal movement of the racks which are removably mounted upon a suitable carriage or carriages adapted to be driven to and fro by any desired reciprocating mechanism.

It is further an object of my invention to provide a rectangular frame, above referred to, with hook devices at its ends to enable said hooks to engage in suitable hanger eyes carried by opposing sides of an open rack, so as to position each frame transversely and diagonally across the rack, thereby forming an assembly unit capable of accommodating a very large number of hides which may be readily hung therein and subsequently bodily disposed in or removed from the vat of tanning liquor by hoisting apparatus of a conventional type.

Other objects and advantages of the invention will be hereinafter set forth and the novel features thereof defined by the appended claims.

In the drawings:

Figure 1 is a perspective view of a tanning apparatus embodying my invention;

Figure 2 is a perspective view of a carriage for supporting the hide racks;

Figure 3 is a perspective view of the rack element used in my apparatus;

Figure 4 is an enlarged fragmentary sectional view, showing more clearly the arrangement of the hide-supporting frames and hides mounted therein;

Figure 5 is a detail perspective view of the mounting end of a hide-supporting frame and its cooperating rack supports and hide clamp;

Figure 6 is a detail view of the hide-clamping or holding bar used in conjunction with the hide-supporting frames;

Figure 7 is a transverse sectional view taken about on the plane indicated by line 7—7 of Figure 4 showing a slightly modified method of hanging the hides in the hide supporting frame;

Figure 8 is a top plan of a slightly modified form of apparatus embodying a plurality of racks and carriages designed to reciprocate in opposing relation to each other;

Figure 9 is a diagrammatic view of a modified form of apparatus in which the racks with their supporting frames are oscillated in the tanning vat;

Figure 10 is a longitudinal sectional view of a modified form of apparatus in which the racks and frames are reciprocated in a vertical plane in the vats instead of a horizontal plane;

Figure 11 is a fragmentary view, partly in section and partly in elevation, of the rack and hide supporting frames used in the apparatus of Figure 10; and

Figure 12 is a fragmentary sectional view taken on the plane indicated by the line 12—12 of Figure 11.

Referring to the drawings, and specifically describing my invention, 1 designates a tank or tanning vat adapted to receive tanning liquors. At each end of this vat, a track member 2 is provided and upon these is supported a carriage 3 which comprises an open rectangular frame 3 having wheels or rollers 4 at each end. This carriage, best seen in Figure 2, is adapted to be shifted to and fro by any desired mechanism, that shown for this purpose being merely exemplary of one type, and consisting of the motor 5 which drives a worm shaft 6 and worm gear 7 to which is eccentrically connected a crank 8. The crank in turn is connected to a lever 9 pivotally secured at one end to the end of the vat and at its other

end adjustably connected to an endless cable 10. This cable is secured to the carriage 3, as by means of the arched arm 11.

In the use of this apparatus, it is to be understood that the hides are supported in a novel form of rack which is removably mounted in or disposed upon the carriage 3. This rack, as seen in Figure 3 of the drawings, conforms to the shape of the carriage, and is constructed of open parallel side frames 12 and end frames 13. Each of these end frames has a solid panel 13' at one end and a window opening 13'' at its other end, for reasons to be more clearly pointed out as this description proceeds.

15 Along the top and bottom rails of the side frames 12 are secured a series of eyes or hangers 14 in which hooks on the hide-supporting frames later to be described are received.

20 In order to suspend this rack in the carriage 3, the ends 13 are provided with lateral extensions or arms 15, which are adapted to rest upon the sides of the carriage, as clearly shown in Figures 1 and 4.

25 An important feature of my invention resides in the construction and arrangement of the hide supports or frames, and reference will now be made to Figures 4 and 5 in this connection. Each frame 16 is rectangular in form and provided with a vertical center bar 17 to thereby provide 30 a pair of openings over which the hides are hung in a special manner. At each end, the frame has an upper and a lower hook 18 by means of which the frame is hung in the rack eyes 14 at opposite ends in a diagonal position, as shown clearly 35 in Figure 4 of the drawings.

40 In the operation and use of this apparatus as thus far disclosed, it will be understood that the frame members 16 are first introduced or hung in the rack 13 so as to form a zig-zag arrangement, such as shown in Figure 4, extending from one 45 end of the rack to the other. While, of course, this may be done when the rack is on the carriage and in the vat, as shown in Figure 1, the preferable method employed is to remove the rack from the vat to a convenient place for attaching the hides to the frames.

50 When the frames are in the position above referred to, a hide is attached to each pair of frames in the manner shown in Figure 4, wherein the length of each hide-supporting frame corresponds to one-half of the width of the hide. That is to say, one-half of the hide *a* is tacked or secured to one frame 16a over its openings, and the other half of the hide is attached to the adjacent frame 16b over its corresponding openings.

55 Since it is not desirable to pass fastening members through the thicker portion of the hide along a central line, I employ a bar 19, shown clearly in Figs. 5 and 6, which has at its ends hook elements 20 to engage in the eye 14 to which the two adjacent frames 16a and 16b are connected. Thus the bar 19 will hold the central portion of the hide in the stretched position shown in the drawings and the same method of attachment of the next hide is followed so that the hide will be disposed between the frame 16b and its next adjacent frame 16c. The hide between the last mentioned pair of frames will therefore face in the opposite direction to that which is attached to the frames 16a and 16b. This same arrangement is followed throughout the frames from one end of the rack to the other.

70 It will be understood that in this arrangement the flesh side of the hides faces the racks or con-

tacts with the frames so that in the operation of the apparatus no injury to the grain side from abrasion or pressure will occur and the grain side will directly contact with the tanning liquor and will be subjected to the pressure which forces the liquor to act upon and penetrate the hide as hereinafter set forth.

When the hanger of the hides in the rack has been completed, the rack with the suspended frames is elevated by any suitable hoisting means 10 which is connected to the hook 21 carried by the supporting bars 22 attached to the top rails of the rack device. By this means the rack is bodily lowered into its suspending position in the carriage 3 mounted on the top of the vat. Assuming that the desired tanning liquor has been introduced into the vat, the reciprocating mechanism is now operated, causing the carriage to move the hide supporting frames to and fro. At each reciprocal movement, the liquor is trapped in the 20 pockets formed by the hides and particularly at the apex of each V formation where the hide is thickest, and such trapping has a tendency to force the liquor to penetrate the hides, particularly at the thicker central portion thereof. It will 25 be understood that this reciprocating motion may readily be controlled as to speed of movement, which, in turn, regulates the pressure which is exerted by the liquor in the action of penetration above referred to, and by this means the process 30 of striking the hides is greatly facilitated and the time for completion of the tanning process reduced to a material extent.

During the tanning operation, it is also to be understood that the liquor may be changed as 35 many times as desired without removing the hides from the vat, a drain cock 23 being provided for use in this connection. When the tanning operation has been completed, it is only necessary to apply the hoisting apparatus to the elevating 40 hook 21 and remove bodily the rack with its hide-supporting frames to the location for dismounting the hides therefrom.

In Figure 7 I have illustrated a slightly modified arrangement of the hides. It will be understood 45 that the frames 16 may be made in length, double the width of a half section of the hide in which event, when the hide is attached to the frames in the same manner hereinbefore described, the half section attached to the frame 50 16a of Figure 4 will cover the opening 16' and the other half section of the hide will cover the opening 16' of the next frame 16b. This will leave the openings at the other ends of the frames uncovered and allow the tanning liquor to act 55 upon the flesh side of the hide as well as upon the grain side.

I therefore desire it to be understood that I do not wish to be restricted as to the particular manner in which the hides are attached to the 60 frames other than that they should follow the general arrangement so as to produce pockets in the apex portion of the V-formation of the frame.

In Figure 8 of the drawings, I have illustrated 65 a slight modification of apparatus wherein two racks A and B are arranged in the same vat. By suitable connection of the arching arm 11a to one strand of the endless member 10a and the other arm 11b to the other strand of the member 10a, the two racks may be moved simultaneously in opposing directions. This greatly facilitates the operation of tanning with a larger number of hides, and the reciprocating action of the respective racks A and B in this arrangement has 70 75

a tendency to increase the pressures of the liquor upon the hides hung in the respective racks.

I desire it to be understood that the foregoing arrangement and operation of this apparatus may be modified in various ways, and I do not wish to be restricted to the details of construction hereinbefore set forth.

As exemplifying a further method and apparatus for tanning hides, reference is made to Figure 9 wherein the rack constructed and arranged in accordance with that hereinbefore described is suspended from a support 24, so that the racks depend into the vat and may be swung about said supports in any desired manner. To this end, as diagrammatically shown, a crank wheel or gear 25 is connected by the rod 26 to the suspending arms 27 of the rack which will thus be oscillated to and fro in the liquor contained in the vat.

In all of the forms of the apparatus above set forth, the rack or racks and frames are moved in substantially a horizontal plane to and fro, but this same arrangement may be employed in an apparatus in which the frames are moved upwardly and downwardly in the tanning vats to accomplish the same result. Such an arrangement as just referred to is disclosed in Figures 10 to 12 of the drawings wherein the rack member 28 is formed at one side with sockets or openings in the top and bottom side rails 28' to receive the ends of cross rods 29, whereas the opposite top and bottom rails 28'' are provided with open slots to receive the opposite ends of said bars or rods. With these open slots 30, slide bolts 31 are adapted to co-act so as to engage with the ends of the bars and lock them in place.

Hide-supporting frames 32 are arranged in the rack so as to form the vertical up and down zig-zag arrangement corresponding to the horizontal zig-zag arrangement of the preferred form and the bars 29 are disposed intermediate the contiguous ends of the frame, as best seen in Figure 11 of the drawings. Each of these bars is provided with a series of pins or penetrating elements 33 which are passed through the central or thicker portion of the hide in sustaining these hides in the racks.

Any method of procedure may be followed in hanging these hides so as to be stretched in the V-formation between the co-acting supporting frames. The edges of the hides may thus be fastened or tacked to one end of the frames and then a bar 29 is engaged with the central portion in the manner shown, one end of the bar being then slipped into the socket on the rack and the other end being elevated into the open slot at the other side of the rack. By sliding the bolt under the last mentioned end, the hide will then be stretched in the V-form between the two frames and will readily be removable therefrom by a reversal of the operation just described.

The rack with its hides mounted therein is now introduced into a tanning vat 34 and suspended by means of its arms 35 from the end of a rocking bar 36 through the linkage 37. The bar or beam 36 is pivotally mounted intermediate its length on a standard or support 37' mounted on the top of the vats, there being in this case two such vats, as shown clearly in Figure 10. The other end of the beam, it will be understood, carries a second rack structure corresponding to that just described in all essential characteristics. Rocking movement is imparted to the beam by any well known actuating means, that illustrated in the drawings diagrammatically consisting of the motor 38 for operating a worm shaft and

worm 39, which in turn operates the worm gear 40 to which the connecting rod 41 is eccentrically connected at one end. The other end of this rod 41 is connected to the beam at a point to one side of the central beam pivot 42, as at 43.

It will be obvious that the degree of lift imparted to the hide supporting racks may be controlled by shifting the point of attachment of the rod 41 toward or away from the beam pivot 42. In this connection there is shown a connecting pin 44 for this purpose.

In the operation of this form of the apparatus, the hides mounted in the supports are moved upwardly and downwardly in the tanning liquors in the respective vats and pressure is exerted by the pocketing action of the hides, tending to force the liquors to penetrate the same in a comparatively short period of time. The action of the apparatus illustrated in Figure 10 will thus be substantially the same as that of the preferred form, but by this type of structure I am enabled to take advantage of the rocking apparatus which is in conventional use at the present time.

It will be obvious from the foregoing description that in the use of my method and apparatus for tanning hides as hereinbefore disclosed that the ingredients of the tanning liquor are kept constantly agitated, so that the tendency heretofore experienced of the settling of the non-tannin ingredients in the form of a sludge is eliminated. This is an important factor because it is desirable to employ the insolubles or non-tannin ingredients for the purpose of "plumping up" or loading the hides, and, in view of the pressures which are obtainable in the operation of the hide-supporting constructions disclosed, these materials will be caused to penetrate into the pores of the hides in a remarkably short period of time as compared with the absorption action in the usual conventional methods. Thus, the non-tannins usually lost in the previous methods will be availed by virtue of the construction and operation of my invention.

While the specific details of construction have been herein shown and described, the invention is not confined thereto, as alterations may be made without departing from the spirit thereof as defined by the appended claims.

Having thus described my invention, what I claim as new as desire to secure by Letters Patent is:

1. Hide tanning apparatus of the class described, comprising a rack and hide supporting means disposed in said rack and having means for fixedly holding the sides of a hide thereon in such spaced position as to form a pressure pocket for trapping the tanning liquor during tanning operation and forcing said liquor to penetrate the hide.

2. Hide tanning apparatus as set forth in claim 1, wherein the supporting means is provided with spacing members for rigidly holding hide sides at an angle to each other so as to support the hide therebetween with its side sections diverging and forming a pressure pocket tending to free the tanning liquors to penetrate the hide.

3. Hide tanning apparatus of the class described, comprising a plurality of hide supporting frames, means for holding said frames in angular relation to each other with an edge of one frame contiguous to an edge of another, and means for fixedly attaching the hide sides in open position between the frames with the sides spaced from each other to effect concentration of the pressure of liquor on the thicker portion of the hide.

4. Hide tanning apparatus of the class described, comprising a plurality of hide supports constructed and arranged to fixedly hold hide sides spaced apart forming V-shaped liquor receiving pockets between the sides, and means for moving said supports in the direction of facing of the pockets to thereby trap the liquor in the pockets under the pressure of said moving means to force the liquor to penetrate the hide.
5. Hide tanning apparatus of the class described, comprising a movable rack adapted to be disposed in a tanning vat, a plurality of substantially rectangular hide supporting members, means for supporting the said members in angular relation to each other in substantially zig-zag position within the rack, and means for fixedly sustaining the hides relative to each pair of hide supporting members so as to form pockets in which to trap the tanning liquor as the rack is moved therein.
10. Hide tanning apparatus of the class described, comprising a movable rack adapted to be disposed in a tanning vat, comprising a substantially rectangular rack structure consisting of spaced open side and open end frame members, rectangular hide stretching frames to which the hides are fixed in stretched V-form each having hanging means at its ends, supporting means on the side members of the rack for receiving the frame hanging means aforesaid to dispose said frames transversely of the rack structure, and means for moving the hides to force the liquor to be concentrated between open sides of said hides.
15. Hide tanning apparatus of the class described, a unitary hide support adapted to be disposed in a tanning vat, comprising a substantially rectangular rack structure consisting of spaced open side and open end frame members, rectangular hide stretching frames to which the hides are fixed in stretched position, and means for supporting said frames between the side members of the rack structure in transversely zig-zag formation from end to end of the said structure so as to form liquor trapping pockets between the frames when the hides are disposed thereon.
20. Hide tanning apparatus of the class described, the combination with a tanning vat and a carriage movable to and fro along the same of a unitary hide supporting structure adapted to be mounted on the carriage and composed of a plurality of hide stretching frames, and means for holding said frames in a zig-zag formation at an angle to each other, means for hanging hides in fixed stretched position about the angle between each pair of frames so as to form a series of liquor trapping pockets, and means for moving the carriage and support-
- ing structure to and fro to cause tanning liquor in the vat to be pocketed by the hides under pressure in the back and forth strokes of the said structure.
25. Tanning apparatus as set forth in claim 8 wherein the carriage is mounted to move on tracks on the top of the vat, and the supporting structure is composed of a rectangular rack in which the hide supporting frames are removably mounted transversely of the rack.
30. Tanning apparatus of the class described, comprising a supporting structure, hide supporting frames mounted on said structure to which the hides are adapted to be connected to rigidly hold the sides of the hides in open stretched V-shaped pocket position, means for moving the structure to and fro and means intermediate the frames for sustaining and holding the hides in said stretched positions with the hides pockets facing in the direction of movement of the structure so as to gather tanning liquor thereinto during movement and prevent escape thereof except through the hides.
35. Tanning apparatus as set forth in claim 10, combined with means for rocking the structure up and down to force the tanning liquor to be trapped between the hide sides.
40. Tanning apparatus of the class described, comprising a rack member having a pair of spaced side rails, one of said rails having rod receiving openings therein and the other of said rails having open slots in which the ends of the rods are engaged, stretching rods arranged in said openings and slots, locking bolts for engaging the ends of the rods which are received in the open slots, and hide supporting frames disposed in the rack in cooperating position, said frames being spaced a greater distance apart at one side than at the other so as to provide a substantially V-formation.
45. In hide tanning apparatus of the class described, the combination of a tanning vat, hide supporting means therein comprising a plurality of frames, each consisting of means for stretching the hides and holding the sides thereof spaced apart so as to form liquor trapping pockets of the hides, and means for moving the frames in the vat in the direction of opening of the pockets to force the liquor into the pockets under pressure and thereby cause penetration of the hides by the liquor.
50. Hide tanning apparatus as set forth in claim 13, wherein the frames and hides are arranged alternately with the pocket openings facing in opposite directions.
55. CHARLES KANNEL.
